Primary Examiner — R. Johnson(74) *Attorney, Agent, or Firm* — Fredrikson & Byron P.A.(57) **CLAIM**

I claim the ornamental design for a chiffonier, as shown and described.

DESCRIPTION

FIG. 1 is a top, front, right perspective view of a chiffonier showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof, the left-side elevational view being a mirror image thereof; and,

FIG. 7 is a cross-sectional view thereof, taken along line 7-7 in FIG. 2.

Where included, broken lines showing environment or structure are for illustrative purposes only and form no part of the claimed design.
